LOCK

Leonard S. Collins, Detroit, Mich.

Application May 29, 1937, Serial No. 145,458

1 Claim. (Cl. 292—173)

This invention relates to locks, more particularly those of the type generally known as night latches, and has for its object to provide in such a lock simplicity of mechanism with positive locking action where and when required and tamper-proof characteristics.

A further object is to provide in such lock mechanism, a swinging lever with a relatively movable operating member adapted to cooperate with stop or detent means to positively lock the lever in one or other of its bolt setting positions. It is also proposed to so form the lever that the main arm thereof will act as a stop against the rear end of the bolt when the bolt is moved to its closed position.

The invention further and more particularly contemplates the provision, in the cover plate, casing, or other overlying part of the lock, a substantially Z-shaped slot in which the aforesaid movable member is guided and in which the said movable member may be locked against mischievous or inadvertent displacement from an "open" or "closed" position by virtue of its engagement in one or other of the terminal legs of the said slot. Still further, the invention provides, where thought necessary or desirable, for snap means or catches, yieldable or otherwise, designed to prevent accidental engagement or disengagement of the operating member in or from said terminal legs of the slot.

Still further objects and advantages subsidiary to or resulting from the invention as it may be carried into effect, will become apparent as the said invention is hereinafter further disclosed.

In carrying the said invention into effect, I may provide in a lock, a slidably mounted bolt movable by one arm of a bell-crank lever the other arm of which carries an operating pin or member movable thereon and guided in a Z-shaped slot in the lock casing, the lever being actuated by movement of the said pin along the main part of the said slot and locked in one or other of its bolt-operating positions by engagement of the said pin in one or other of the terminal legs of the said slot, and yieldable catches resisting movement of the said pin into and out of the said legs of the slot, the last mentioned arm of the said lever preferably so co-acting with the inner end of the said bolt that it will act as a positive stop against retraction of the said bolt when said lever is moved to effect the closing of the bolt on its keeper. The keeper is proposed to be in the form of a member with a slotted head entering and concealed by the lock casing and provided with an annular shoulder extending

about the opening of the casing through which the keeper enters.

All of which is more particularly described and ascertained hereinafter by way of example having reference to the accompanying drawing, 5 wherein:

Figure 1 is a perspective view of the base plate of the lock and the parts carried thereby;

Figure 2 is a similar view of the cover plate or casing;

Figure 3 is an elevation of the said lock; and

Figure 4 is a perspective view of the keeper.

Similar characters of reference indicate similar parts in the several figures of the drawing.

1 indicates the base plate of the lock, on which the bolt 2 is slidably mounted by virtue of its slotted engagement with guide pins 3 and 4. 5 is a bell-crank lever pivoted on the stud 6 and having its shorter arm 7 extending into a recess 8 in the said bolt, the long arm 9 of the said 20 bell-crank lever extending materially beyond the rear end of the bolt which is shown as having a cam surface 10 against which an inner edge of the arm 9 of the bell-crank lever will engage when the said lever is moved to the position 25 shown in Figure 1, wherein the bolt is projected forwardly or "closed."

11 is a bow spring mounted on a pin 12 and engaging the rear end of the said bolt urging the same forwardly.

The arm 9 of the bell-crank lever is shown as being slotted at 13 and provided with a sliding shoe 14 from which a pin or shaft 15 extends perpendicularly through the said slot 13, the said pin being thereby movable laterally of its axis and 35 along the said slot 13.

When the cover plate 16 is assembled on the base plate 1 to house the mechanism described, the pin 15 extends outwardly of the said cover plate through a slot 17 having offset terminal legs 18 and 19, the said slot being, therefore, of a generally Z-shaped formation; and it will be readily apparent that movement of the pin 15 in one or other direction along the slot 17 will effect the pivotal movement of the bell-crank 45 lever and consequently determine the opening or closing movement of the bolt. It will also be recognized that when such movement is effected to its limits, the said pin 15 by virtue of its slotted mounting in the arm 9 of the bell-crank 50 lever may be moved into the offset leg 18 or the leg 19, as the case may be, of the slot 17, and that when it is so engaged in one or other of the said legs 18 or 19 movement of the bell-crank lever in one or other direction is effectively pre- 55

vented by the walls 18' and 19' of the legs 18 and 19 of the slot 17, these walls thereby acting as offset detents for the said pin at the ends of the said slot 17.

5 To prevent accidental displacement of the pin in its engagement with one or other of the said legs 18 or 19, such as under the influence of vibration, suitable catches such as spring stops 20 and 21 may be provided at or proximate to the 10 entrance of the said legs, to yieldably resist the movement of the pin 15 into and out of the legs 18 and 19 of the slot 17.

While the arrangement described is primarily intended as a night-latch mechanism operable solely by means of the said pin 15, which may be provided with any convenient form of handle or knob (not shown) for that purpose, any suitable provision may be made for key or other operation from the opposite side of the lock, and 20 in the drawing 22 indicates a lock cylinder or its housing, such as may enclose the usual key operable tumbler mechanism for the purpose of controlling the rotation of a gear 23, or equivalent means, adapted to reciprocate the bolt as 25 through the agency of rack teeth 24 formed on the said bolt. Where the bolt is so operated the bell-crank lever will be rocked by the movement of the bolt, the pin 15 freely moving in one or the other direction along the length of the main 30 slot 17, and in this case the spring catches 20 and 21 serve to prevent inadvertent slipping of the said pin into one or other of the legs 18 or 19 of slot 17 such as might result in undesirable

locking of the elements against key operation; although it will be readily apparent that the pin may be manually and deliberately so engaged with the said slot legs for security as and when desired.

5 A suitable form of keeper may be in the form of a cylindrical member 24 having annular shoulder 25 beyond which extends a cylindrical head 26, slotted at 27, and adapted to coact with a bevelled face 28 on the forward end of the bolt 10 to provide a snap action, the cylindrical head 26 entering the casing through a corresponding cylindrical opening 27 in the base plate and the shoulder 25 overlying the margins of said opening when the lock is closed on the keeper. 15

This invention may be developed within the scope of the following claim without departing from the essential features of the said invention and it is desired that the specification and drawing be read as being merely illustrative and not 20 in the limiting sense, except as necessitated by the prior art.

What I claim is:

In a lock, a bolt, a swinging bolt-actuating lever, said lever in its bolt-projected position moving into the path of said bolt to act as a stop thereagainst, a lever-operating member attached to said lever, a cover plate having a guide slot therein for said member, and detent means at each end of the guide slot with which said member may be manually engaged to prevent its movement in said slot. 30
